(57) **CLAIM**

I claim the ornamental design for a fishing flasher lure, as shown and described.

DESCRIPTION

FIG. 1 is a perspective view of the design for a fishing flasher lure;

FIG. 2 is a top view of the design of FIG. 1;

FIG. 3 is a bottom view of the design of FIG. 1;

FIG. 4 is a right side view of the design of FIG. 1;

FIG. 5 is a left side view of the design of FIG. 1;

FIG. 6 is a rear view of the design of FIG. 1; and,

FIG. 7 is a front view of the design of FIG. 1.

The broken lines in the drawing figures are shown for illustrative purposes only and form no part of the claimed design.
